UNITED STATES PATENT OFFICE.

CHARLES W. SCHMUESER, OF WILL'S CREEK, OHIO.

WINDLASS WATER-ELEVATOR BUCKET.

SPECIFICATION forming part of Letters Patent No. 314,061, dated March 17, 1885.

Application filed October 29, 1884. (No model.)

To all whom it may concern:

Be it known that I, CHARLES W. SCHMUESER, a citizen of the United States, and a resident of Will's Creek, in the county of Coshocton and State of Ohio, have invented certain new and useful Improvements in Devices for Carrying Water from Wells and Springs; and I do hereby declare that the following is a full, clear, and exact description of the invention, which will enable others skilled in the art to which it appertains to make and use the same, reference being had to the accompanying drawings, which form a part of this specification, and in which—

15 Figure 1 is a side view of a device for carrying water from wells or springs, provided with my improved bucket and bail. Fig. 2 is a horizontal section on line *x* *x*, Fig. 1. Fig. 3 is a perspective detail view of the 20 bucket with its weighted yoke; and Fig. 4 is a view showing the bucket being automatically emptied.

Similar letters of reference indicate corresponding parts in all the figures.

25 My invention has relation to buckets for water-elevators for wells and springs; and it consists in the improved construction and combination of parts of such a bucket, having a weighted yoke which will facilitate the 30 filling of the bucket, as hereinafter more fully described and claimed.

In the accompanying drawings, the bucket is shown used in a so-called "windlass-elevator," having the elevator-rope passing over pulleys 35 upon a carriage which travels upon an inclined track, and although I prefer this construction I do not confine the use of the bucket to this construction of an elevator.

In the drawings, A indicates the inclined 40 track; B, the carriage; C, the bucket; D, a pulley upon the bail of the bucket, and E the hoisting-rope, which is secured at one end to

the carriage whereupon it passes over the pulley D and over a pulley in the carriage to a suitable windlass or other hoisting apparatus. 45

F is the well, having posts G and grooved ways H, in which the outwardly-projecting ends J of a yoke, K, slide. The ends J of this yoke K pass through the ears I of the bucket, and the bail L, to the upper end of which the 50 pulley D is secured, is secured with its lower ends to the ends of this yoke, while a cross piece, M, having a weight, N, pending from it, is secured with its ends between the sides of the yoke, which has the shape of an oblong 55 loop.

O is a chute into which the bucket is emptied, having a cut-off front edge, P, and a projecting horn, Q, adapted to engage the yoke K and hold it while the bucket is tilted and 60 emptied.

It will be seen that as the bucket on being lowered will strike the water the weighted yoke will tilt the bucket and force its rim under the water, allowing it to be filled, when 65 the bucket may again be drawn up and emptied.

I make no claims for the hoisting or emptying mechanism; but

70 I claim—

The combination of the bucket, the bail, the oblong yoke having its ends projecting through the ears of the bucket, and the weight suspended from and between the arms of the yoke, keeping the latter in a horizontal position, as and for the purpose shown and set forth. 75

In testimony that I claim the foregoing as my own I have hereunto affixed my signature in presence of two witnesses.

CHARLES W. SCHMUESER.

Witnesses:
